UNITED STATES PATENT OFFICE.

FRANK B. DILLARD, OF OAKLAND, CALIFORNIA.

ADJUSTABLE TOILET SEAT.

Application filed November 6, 1922. Serial No. 599,336.

To all whom it may concern:

Be it known that I, FRANK B. DILLARD, a citizen of the United States, residing at Oakland, in the county of Alameda and 5 State of California, have invented new and useful Improvements in Adjustable Toilet Seats, of which the following is a specification.

This invention relates to improvements in 10 adjustable toilet seats.

The principal object of this invention is to construct a toilet seat which may be easily and rapidly adjusted to provide for the accommodation of various individuals.

15 Another object of this invention is to provide a device of this character which is cheap to construct, neat in appearance and one which may be employed with the usual toilet base.

20 Other objects and advantages will be apparent during the course of the following description.

In the accompanying drawings forming 25 a part of this specification, and in which like numerals are employed to designate like parts throughout the same,

Figure 1 is a top plan view of my device,

Figure 2 is a cross-section taken on the line 2—2 of Figure 1, and

30 Figure 3 is an enlarged detail cross-section taken on the line 3—3 of Figure 2.

It is now customary to employ auxiliary toilet seats for children, which seats are superimposed upon the ordinary seat; or 35 to use a separate chair having a receptacle therein. Both of these methods are troublesome, and the use of a separate receptacle is unsanitary as these receptacles are often upset and broken. In traveling or in theatres and the like, accommodations for children are not provided, and it is to provide 40 for their convenience that I have devised my invention, which consists of expandable seat portions which may be moved to or away 45 from each other, thus providing an expandible toilet seat for individuals of all ages.

In the accompanying drawings, wherein 50 for the purpose of illustration is shown a preferred embodiment of my invention, the numerals 5 and 6 refer to two seat portions of a toilet seat, which rest on the usual bowl 23. These seat portions are curved and are secured to a cross piece 7 through the medium of channels 8 and 9, which engage T 55 members as shown at 11 and 12. The T

members are secured to the cross piece 7, while the channels are secured to each of the seat pieces 5 and 6. A recess 13 is provided on each of the seat pieces, within which recess is mounted a nut 14. This nut 60 14 is adapted to engage a worm 16, and it will be noted, by viewing Figure 2, that this worm 16 is formed upon the shaft 17 and is pitched in opposite directions from its medial line toward each end. A handle as 65 shown at 18 and 19 is secured to each end of the shaft 17 for the purpose of rotating the same. Suitable bearings 21 and 22 are secured to the cross piece 7 and serve to prevent lateral movement of the shaft 17.

The numeral 23 designates the usual porcelain bowl of the toilet to which is secured a pintle 24 to which the cover 26 is hinged as by members 27 and 28. Similar members 29 and 31 serve to hinge the crosspiece 7 to the pintle 24.

It will thus be seen that by rotating the shaft 17 through the medium of one of the handles, as for instance the handle 19, the worms 16 will be caused to rotate. As these 80 worms are pitched in opposite directions, the result will be that the nuts 14, which are secured to the seat portions 5 and 6 will be caused to move to or away from each other depending upon the direction of rotation of the shaft 17, thereby adjusting the distance between the seat portions for the accommodation of the person using the toilet.

It is apparent that I have devised a very 90 simple, efficient and quick means for accomplishing the above result, and one which may be applied to the standard porcelain bowl now in general use.

It is to be understood that the form of my 95 invention herewith shown and described is to be taken as a preferred example of the same, and that various changes in the shape, size and arrangement of parts may be resorted to without departing from the spirit 100 of the invention or the scope of the subjoined claims.

Having thus described my invention, I claim:

1. In a device of the character described, 105 a cross piece, a shaft mounted on said cross piece, worms formed on said shaft, and substantially semi-circular seat portions slidably secured to said cross pieces and adapted to be simultaneously moved toward or away 110

from each other through the rotation of a worm formed on opposite sides of the said shaft.

2. In a device of the character described, a cross piece, a shaft rotatably mounted therebelow, substantially semi-circular seat portions slidably secured to said cross piece, a nut mounted on each of said seat portions, a dial line of said shaft, said worms being pitched in opposite directions and adapted to be engaged by said nuts, substantially as and for the purpose specified.

In testimony whereof I affix my signature.

FRANK B. DILLARD.
